CLAIM

The ornamental design of a planter row panel unit, as shown and described.

DESCRIPTION

FIG. 1 is a perspective view of a planter row panel unit showing our new design, the center supports shown in broken lines are for illustrative purposes only; FIG. 2 is a side elevational view of the right panel of FIG. 1, shown separately for ease of illustration; FIG. 3 is a top plan view of FIG. 2;

FIG. 4 is a bottom plan view of FIG. 2;

FIG. 5 is a left end elevational view of FIG. 2;

FIG. 6 is a side elevational view, opposite that shown in FIG. 2;

FIG. 7 is a right end elevational view of FIG. 2;

FIG. 8 is a side elevational view of the left panel of FIG. 1, shown separated for ease of illustration;

FIG. 9 is a top plan view of FIG. 8;

FIG. 10 is a bottom plan view of FIG. 8;

FIG. 11 is a right end elevational view of FIG. 8;

FIG. 12 is a side elevational view, opposite that shown in FIG. 8;

FIG. 13 is a left end elevational view of FIG. 8.
